(57) **CLAIM**

The ornamental design for a camera housing with sunshield, as shown and described.

DESCRIPTION

FIG. 1 is a front-right-top perspective view of a camera housing with sunshield embodying the new design;

FIG. 2 is a rear-right-top perspective view thereof;

FIG. 3 is a front elevational view thereof;

FIG. 4 is a rear elevational view thereof;

FIG. 5 is a bottom plan view thereof;

FIG. 6 is a top plan view thereof;

FIG. 7 is a left side elevational view thereof;

FIG. 8 is a right side elevational view thereof;

FIG. 9 is a front-right-top perspective view illustrating the camera housing without the sunshield;

FIG. 10 is a top plan view thereof;

FIG. 11 is a right side elevational view thereof, the undisclosed left side elevational view being identical thereto;

FIG. 12 is a front, left and bottom perspective view illustrating sunshield, the camera being omitted for ease of illustration;

FIG. 13 is a bottom plan view thereof; and,

FIG. 14 is a front elevational view thereof.

The broken lines in the figures are shown for the purpose of illustrating environmental matter and form no part of the claimed design.
